J. E. DEKKER

CAN OPENER

Filed March 21, 1925

Inventor
John E. Dekker
by Arthur M. Nelson, Atty.

UNITED STATES PATENT OFFICE.

JOHN E. DEKKER, OF CHICAGO, ILLINOIS.

CAN OPENER.

Application filed March 21, 1925. Serial No. 17,191.

This invention relates to improvements in can openers and in the method of making the same and it consists of the matters hereinafter described and more particularly pointed out in the appended claims.

In can openers of the kind employing a rotary shearing element or cutter mounted on a guide rod or support which includes a can head piercing tip at one end and a handle at the other end, efficiency requires the hardening of said guide rod and tip after they have been formed to the desired shape. This hardening is impractical in cutter guides embodying an integral piercing tip as heretofore made because in the heating of the same, during the hardening process, the tip by reason of its being of a diameter less than the guide, reached the proper heat first. If the heating was discontinued at this point, the guide was still relatively soft and the result would be a hard piercing tip and a relatively soft guide. If the heat treatment was continued to bring the guide up to the proper heat, the tip became over heated so that it was impossible to turn out an article with the guide and tip of the same hardness.

The main object of the present invention is to so construct a can opener of the kind described that both the shear guide and the piercing tip may be made of a uniform hardness.

A further object of the invention is to so make the guide and tip, that the tip which limits the movement of the shear or cutter in one direction on the guide may be removed therefrom without the aid of a tool of any kind to permit the reversal of the cutter from the tip end instead of from the handle end, which reversal is especially desired in cutters employing more than one cutter disc.

My invention further consists in a device of the form, arrangement, construction and cooperation of the parts, as well as the various steps in producing the same, whereby the above mentioned objects together with others as will hereinafter appear are at-

tainable; and my invention will be more readily understood by reference to the accompanying drawings which illustrate what I consider at the present time to be the best embodiment thereof.

In said drawings:—

Fig. 1 is a view in side elevation of a can opener made in accordance with my invention.

Fig. 2 is an enlarged view partly in elevation and partly in section of the can piercing tip end of the opener as it appears when being used for its intended purpose.

Fig. 3 is a transverse section through the guide member, with the cutter element shown in end elevation, the plane of the section being indicated by the line 3—3 of Fig. 1.

The invention is herein shown and will be herein described as being embodied in a can opener of the type shown in my prior Patent No. 1,527,581 granted to me on Feb. 24, 1925. However, I do not wish to be limited to this particular type of can opener because I have mentioned the same by way of illustration only and not by way of limitation, it being apparent that the invention both as to the specific structure of the guide and tip, as well as the method of producing the same, may be embodied in other types of can openers, where its peculiar characteristics make it advantageous to do so.

The device as herein shown comprises four parts or elements, namely, a shear guide or shaft portion 1, a can head piercing tip 2 on one end thereof, a handle 3 on the other end thereof, and a cutter or shear element 4 loosely mounted on the guide or shaft and capable of a rotative as well as a longitudinal movement thereon between limits defined by said tip and handle respectively.

The shear guide or shaft is made in the form of a cylindrical rod of the desired length and preferably of a steel which will readily permit certain machine operations. One end of said rod is turned down to provide a reduced extension 5 which is there-

after exteriorly threaded as shown in Fig. 2, thus forming a radial shoulder 6 on said guide at the inner end of said extension.

In making up the tip 2, I prefer to use a stock of a diameter somewhat greater than that of the rod 1. I find that a tip stock of 10/32 inches diameter and a guide stock of 9/32 inches diameter are about the proper proportions. I turn down the tip stock from a body portion 7 to form an extension 8 of a diameter equaling that of the rod and a piercing tip portion 9 of a diameter somewhat less than said guide. The extreme end of the piercing tip is tapered or pointed as best shown in Fig. 2. It is to be here noted that the tip has longitudinally rounded sides as indicated at 10 and as distinguished from flat tapered sides. These rounded tapered sides better permit the heat treatment in hardening and stands up better in actual use than does the other tapered point before referred to, because it contains more actual stock. After the tip has thus been made, a threaded recess 11 adapted to receive the extension 5 of the guide or shaft 1, is made in the body portion 7 of the tip 2. The portion 9 of the tip stock is then bent or otherwise formed so that the pointed end portion is offset into a plane parallel with but spaced from the axial plane of the body 7. Thus the portions 8 and 10 are connected by a reverse curved portion 12 as best shown in Fig. 2. By means of this construction, after piercing a can head with the point 10, the opener as a whole may be readily swung about the portion 12 so as to bring it from the initial piercing position to the operating position on a can. This reverse curve portion forms the axis about which the can opener is moved when operating upon a can and limits the size of the opening formed in the can head so that the tip cannot be ripped or pulled out in actual use.

After forming the guide 1 and tip 2 as above described they are hardened. As the hardening process includes a heat treatment, a number of the guide portions are treated at one time and a number of tips are treated at another time. In this way uniformity is attained in the hardening of said parts. After hardening the parts are finished either by polishing or plating or both and are ready for assembly with respect to the handle and cutter element.

That end of a guide or shaft, opposite the extension 5 is forced into an opening in one end of a handle member 3 which is preferably made of wood and has the usual ferrule 13 thereon. Before applying the tip I apply a cutter element 4 upon the guide from the extension end and a tip 2 is then applied by screwing the body end upon said extension as shown in Fig. 2, the end of said body portion abutting the shoulder 6 on the guide. The body portion 7 which is knurled

as shown in Fig. 1 for convenient manipulation and also for appearance, provides one stop for the cutter element upon the guide while the handle 3 provides the outer stop.

Preferably I employ a cutter element of the kind as shown in my prior patent before referred to, which cutter element comprises two spaced cutter discs 14 mounted on hub 15 having an opening 16 therein of a diameter much larger than the guide, as best shown in Fig. 3. Said cutter disc has peripheral cutting edges and is adapted to straddle the bead 17 of a can 18 with the hub riding on the can bead as best shown in Fig. 2, with one disc on the inside of the bead and operating as a cutting element in conjunction with the inner surface of the can bead and with the other flange engaging the outside of the bead for guiding engagement therewith, the hub limiting the cutting edge of the active disc to but slight projection below the cover or head 19 of the can to be opened.

Should the active cutting disc become dull or worn through repeated use, the tip is removed and the cutter element then removed from the guide and reversed end for end and then replaced on the guide or rod after which the tip is replaced; thus the former guide disc becomes the active cutting disc and the former active cutting disc becomes the guide disc. As the cutter is made of accurately machined tool steel they last indefinitely but should it be desired to reverse the cutter it is only necessary to pierce a can end and swing the guide into the position shown in Fig. 2 and turn the handle to unscrew the handle from the tip, which is held against turning with respect to the handle while in the can as is apparent.

The many advantages of the improved can opener as well as the method in which it is made will be apparent to those familiar with the art. In describing my invention I have referred in detail to many details of construction as well as steps in the manner of producing the same but the same is for purpose of illustration only, so that I do not wish to be limited thereto except as may be pointed out in the appended claims.

I claim as my invention:

1. A can opener embodying therein, a metallic guide member, a handle mounted on one end of said member, said guide member having a reduced and threaded extension at its opposite end, a can head piercing tip pointed at one end and having a threaded recess at its other end to receive said extension of the guide member, and a cutter element mounted on said guide member between said handle and tip member for both a rotative and a longitudinal movement.

2. A can opener embodying therein, a metallic guide member, a handle mounted on one end of said member, said guide member

having a reduced and threaded extension at its opposite end, a can head piercing tip pointed at one end and having a body at its other end of a diameter greater than that of the guide member, said body of said tip having a threaded recess to receive said extension on the guide member, a cutter element on said guide and capable of both a rotative

and a longitudinal movement thereon, the body of said tip member acting as a stop ¹⁰ to limit the longitudinal movement of said cutter element in one direction on said guide member.

In testimony whercof, I have hereunto set my hand, this 14th day of March, 1925.

JOHN E. DEKKER.
